UNITED STATES PATENT OFFICE.

CHARLES T. HOWSON, OF OWENSBORO, KENTUCKY, ASSIGNOR TO THE ANGLO-AMERICAN MILL CO., OF OWENSBORO, KENTUCKY, A CORPORATION OF KENTUCKY.

SCOURER.

1,372,511.

Specification of Letters Patent. Patented Mar. 22, 1921.

Application filed July 8, 1916. Serial No. 108,133.

To all whom it may concern:

Be it known that I, CHARLES T. HOWSON, a citizen of the United States, residing at Owensboro, in the county of Daviess and 5 State of Kentucky, have invented new and useful Improvements in Scourers, of which the following is a specification.

The present invention relates to scouring machines, and in its present embodiment is 10 described as particularly adapted for use in scouring cereals such as wheat and the like, although it is to be understood that it is not limited to this specific use, as it is adaptable to a variety of uses other than that disclosed, 15 and it may be employed, with slight modifications and changes in adjustments, as a wheat peeler, a debranner, rice polisher, rye scourer and the like.

The invention has as its objects to provide 20 a scourer in which the grain or other material to be treated is thoroughly scoured and completely freed from all foreign particles or impurities which are mixed with or tend to cling to the grain without abrading 25 or otherwise injuring the stock; and to provide a machine in which all collections or accumulations of dust or other foreign matter which might collect vermin or various other forms of fungi, resulting in contamination 30 of the stock, is prevented.

Further objects of this invention are, to provide a simple and compact machine, which may be efficiently operated with a minimum amount of power and which is al- 35 most noiseless in its operation.

In the drawings which accompany and 40 form a part of the specification, I have illustrated one embodiment of my invention, and in said drawings:

Figure 1 is a side elevational view of the entire machine, one of the side doors being removed to disclose parts of the internal construction.

Fig. 2 is a detail view of one end of the 45 scouring case suction hood.

Fig. 3 is a fragmentary sectional view taken on line 3—3, Fig. 1.

Fig. 4 is an elevational view of one end of the device; and

Fig. 5 is an elevational view of the other end of the device.

Fig. 6 is a vertical sectional view taken longitudinally through the entire device.

Fig. 7 is a sectional view taken on line

7—7, Fig. 6, looking in the direction of the 55 arrows.

Fig. 8 is a transverse sectional view on line 8—8, Fig. 6, looking in the direction of the arrows.

Referring to the drawings, wherein like 60 numerals represent like parts in the several views, 10 designates a casing which may be of any suitable construction, but in the present instance, the same is disclosed as consisting of two compartments, one of which 65 compartments contains the instrumentalities for scouring the stock and separating the impurities therefrom, and the other compartment, designated by the numeral 11, serving as a suction casing for a suction fan 12. The 70 two compartments of the machine are placed in communication with each other by means of a tube or box 13.

In the top of the compartment which houses the scouring instrumentalities and 75 preferably adjacent one end thereof is a feed-box 14 open at its bottom end and having an opening in one of its walls, formed by terminating such wall short of the others, to permit the grain to be fed from the box 14 80 onto a reciprocating shoe 15. The shoe is located close to the bottom edge of the box 14 and to prevent grain from leaking through the space between the lower edge of the box and the top surface of the shoe, sheep's wool 85 16, or other suitable packing is secured by tacks or other means to the lower edge of the box.

The side opening in the feed box is provided with an adjustable gate comprising, 90 in the present instance, a flap or gate 17 hinged to a plate 18. The plate 18 has, as shown in Fig. 7, a pair of spaced-apart vertical slots through which pins 19 extend, each of the pins being provided with thumb 95 nuts 20 to permit vertical adjustment of the plate 18 together with the gate 17, but of course, any other suitable means for adjusting the gate vertically may be employed, that shown in the drawings being by way of 100 illustration only. Attached to and extending horizontally from the flap or gate 17 is a threaded rod on which is adjustably mounted a weight 21. By this arrangement, the gate may be raised or lowered to admit 105 more or less grain to the shoe as desired, or the weight 21 may be adjusted upon the rod to which it is connected, to vary the pressure

with which the gate bears against the grain within the feed-box.

The shoe 15 is suspended from the top of the casing by resilient or flexible strips 22 which permit a vibratory or reciprocating movement to be imparted to the shoe by the mechanism hereinafter described. The shoe has a main or top screen 23 onto which the feed-box delivers when the shoe is vibrated. 10 The mesh of this screen is such as to permit the grain to pass therethrough, while the coarser impurities such as sticks, straw, corn, and the like, roll or slide down the main screen to a spout 24 which delivers to 15 the outside of the casing. The grain or seeds fall onto a seed screen 25, which screen delivers the seeds to a hopper 26, while the finer foreign particles, such as broken grain, small seeds, sand and the like, pass through the perforations of the screen onto the solid bottom 27 of the shoe, which delivers them to a spout 28 discharging 20 to the outside of the machine.

The grain delivered by the seed screen 25 to the hopper 26 passes through one end of a suction pipe 29 and falls into a hopper 30 which delivers to the scouring mechanism. The suction pipe 29 leads upwardly and then curves downwardly, as shown in Fig. 8, 30 to a short pipe 31 which delivers to a settling chamber 32. The settling chamber 32 is exactly similar in structure to the settling chamber 33 shown in Fig. 7, and comprises a closed compartment having one side inclined downwardly and outwardly toward the side of the casing. In the side of the casing 10 at the lower end of the inclined wall of the settling chamber is a door 34 by means of which the heavier particles which 35 collect in the settling chamber may be removed. In the lower part of the settling chamber are a pair of plates 35 inclined downwardly and inwardly of the casing and one of these plates pivotally carries at its lower end an auxiliary door 36 which is normally maintained in closed position due to gravity, and by this construction, a pocket is provided in the bottom of the settling chamber, and the auxiliary door 36 40 prevents air from being drawn through the cracks about the outer door 34. Above the outer door is a slot or opening to admit air in to the settling chamber, and the slot has a slide 36' for closing the opening when desired.

The chamber 32 is, furthermore, provided with a depending partition or web 37 which forms a compartment 38 having an open bottom, the current of air through which is 45 controlled by a swinging plate or valve 39. The valve 39, as shown in Fig. 7, is pivoted at one end and is operated by means of a push-rod 40 extending outwardly through the side of the casing to permit ready manipulation thereof. The chamber 32 is in

communication, by means of a transverse conduit or pipe 41 with a suction box 42 extending longitudinally of the casing, and being open at one end, so as to be in communication with the suction chamber 11.

As the grain passes from the hopper 26 in the hopper 30, it falls through the open end of the suction-leg or pipe 29, where it encounters an upward current of air which carries off the chaff, dust, shrunken kernels, and all foreign particles of matter lighter than the grain being treated, and these impurities are carried by the pipes 29 and 31 to the settling chamber 32. The current of air entering the chamber 32 passes beneath the partition 37, the heavier particles dropping into the bottom of the settling chamber from which they may be removed through the door 34, and the lighter particles being carried into the compartment 38 through the conduit 41 into the suction box 42 from which they are drawn by means of the fan 12 through the member 13 into suction casing 11, and they are forced through the outlet of the suction chamber to any suitable collecting receptacle.

The grain in the hopper 30 is carried into a cylindrical scouring case 43 which may be of any suitable type, and while I have shown it, in the present embodiment, as being of reticulated material, it may be constructed of wire cloth, perforated steel, chilled slot cast iron, flat sheet steel, or any other material depending upon the material to be treated.

Extending centrally through the scouring case 43 is a beater shaft 44 which is mounted in suitable bearings 45 in the end walls of the casing 10. The ends of the shaft 44 extend outside of the casing and on one of said ends is removably mounted a pulley 46 by means of which the beater-shaft may be driven, any suitable source of energy being connected up to said pulley. It is, of course, obvious that the bearings 45 may be of any approved construction, but, in the present instance, I have disclosed the same as being of the ball-bearing type, so as to reduce friction to a minimum, and these bearings are carried by removable bearing-boxes 47 which are detachably secured in the end walls of the casing 10, which openings are of slightly greater diameter than the beater section of the shaft, so as to permit removal of the beater endwise of the casing through one of said openings without in any way disassembling the machine.

The end of the beater shaft 44 extending through the suction casing 11 carries the fan 12, and that portion of the shaft which lies within the scouring case is provided with a plurality of beaters or fingers 48. Adjacent one end of the scouring case, the beater shaft has a pair of spirally arranged flights or flanges 49 which are disposed obliquely to

the longitudinal axis of the beater, and these flights are adapted to force the grain from the hopper 30 into the scouring case under pressure.

5 The beaters or fingers 48 extend radially from annular rings 50 which fit over the shaft, and when assembled, form a cylinder. Each of the rings is connected to the next succeeding ring by small lugs 51 which engage in notches or recesses in adjacent rings, and by this arrangement, angular relative displacement of the rings is prevented. The beaters or fingers 48 are corrugated radially with respect to the axis of the shaft 44, and 10 each of the corrugations of the fingers are divergent so that each corrugation successively presents its rubbing surface to the grain with increased pressure, it being understood that the beater-shaft is adapted to 15 rotate in a direction to cause the narrow edge of the beaters 48 to enter the stock being treated. The corrugations of the beaters 48 have rounded or smooth corners which prevent the liability of the stock breaking 20 and cause a general but continuous rubbing of the beaters against the stock, the stock against the stock, and the stock against the scouring case, and thus a gentle and non-abrasive scouring action results, which does 25 not injure or crush the stock, but evenly removes all foreign particles capable of being removed from the wheat or grain.

The scouring of the grain or wheat is accomplished in the interior of the case by the 30 fingers scouring the wheat or grain against itself, the grain being scoured continuously from the inner periphery of the case to the beater-shaft in the center of the case. The scouring which is done between the ends of 35 the beaters and the inner surface of the case is incidental to the scouring by the beater-fingers against the grain, and the stock against the stock. To form a more or less air-tight joint about the shaft 44 and 40 to reduce friction where it extends through the end walls of the compartment of the casing 10, which contains the beater, I provide leather washers 52 upon the shaft which engage the inside surfaces of said 45 walls.

The scouring case 43 is surrounded by or housed in a suction hood 53, which, in the present instance, comprises a somewhat elongated flat casing split longitudinally and 50 vertically into two parts as shown in Fig. 7. The upper portion of the suction hood is curved transversely and concentrically to the scouring case 43, and is set closely thereto, while the lower end of the hood depends 55 for some distance beneath the lower edge of the scouring case, thereby providing a narrow annular passage about the top and sides of the scouring case, and an unobstructed passage in the bottom of the hood. Along 60 the top of the hood 53, and running the full

length thereof is a slot 54, and the suction hood is in communication with the suction chamber 11, through the connecting pipe 55, and thus the fan 12 draws the air together with the particles which pass through the 70 perforations of the scouring case from the suction hood. By providing the slot 54 along the top of the hood, a strong current is caused to sweep around the scouring case and through the same drawing out all fuzz, 75 beeswing, dirt, and the like, liberated from the grain by the action of the beaters 48. The end wall of the suction hood opposite the pipe 55 is provided with a number of small openings 56 which allow air to enter 80 the hood and clean the corners of all scourings, dirt, and the like. By ventilating the hood 53 and the casing 43 in the manner described, the necessity of an extra set of spouting now generally used in the standard 85 types of machines for drawing off the foreign particles, is obviated, and all collection or accumulation of foreign matter in the interior of the suction-hood 53, which might tend to collect growths which would contaminate the stock being treated, is eliminated. The two parts of the hood 53 may be secured together in any suitable manner, but in the present embodiment, I have disclosed this means as comprising pivoted 90 latches 56'.

At the discharging end of the scouring case is a sleeve 57 into which the beater-section of the shaft extends and which discharges into a discharge chute 58. The 100 sleeve 57, as shown in Fig. 3, is open at one side, which opening is normally closed by a retarding valve 59. The retarding valve 59 comprises a plate fixed along its upper end to a pivoted shaft 60 which at one end 105 extends outwardly beyond the side of the casing and upon this outwardly extending end is fixed a horizontally extending arm 61 carrying an adjustable weight 62.

The retarding valve 59 serves as a regulator for retaining the wheat or other stock being treated under suitable pressure within the scouring case, and the pressure upon the wheat may be varied by adjusting the weight 62 lengthwise of the arm 61. The 110 wheat is forced by the spirally arranged lights or feeders 49 upon the beater shaft from the hopper 30 into the scouring case 43, where the wheat is subjected to the scouring or rubbing action of the web-shaped 115 beaters or fingers 48. The pressure with which the valve 59 retains the stock in the scouring case, while being scoured, determines the degree of scouring, a greater pressure allowing a harder rubbing action by the 120 beaters, and, therefore, a more thorough scouring of the grain. The same amount of stock is delivered by the flights 49 into the scouring case at all times, and the feeding 125 of the stock is independent of the pressure 130

to which the stock being scoured is subjected, and thus the capacity of the machine may be worked to its limit, although the pressure with which the stock is retained in the case by the valve 59 may be varied. The feeders 49 control the amount of stock being fed into the scouring case, and this amount of stock is uniform, although the retarding valve may be adjusted to retain the stock under greater or less pressure within the case.

The discharge chute 58 forms a part of a suction pipe 63 which, as shown in Fig. 4, extends upwardly into the casing and curves downwardly, so as to deliver into the short pipe section 64, which discharges into the settling chamber 33. The settling chamber 33 which is described above, is in all respects similar to the settling chamber 32, and is connected to the suction-box 44 by means of a transverse conduit 65.

By the latter arrangement, the finer particles of dust and other impurities which may have escaped the suction action while passing through the scouring case are again subjected to a current of air which enters the discharge chute 58, passes through the pipes 63 and 64 into the settling chamber 33, where heavier particles drop into the bottom of the settling chamber and are withdrawn therefrom through a side-door in the casing. The lighter particles are carried through the conduit 65 into the suction box 44 and from thence are drawn, by means of the fan 12, into the suction chamber 11.

It will be noted that the grain or stock being treated is subjected to three distinct currents of air, it being subjected to one current of air before passing into the scouring case, a second current of air while in the scouring case, and a third current of air after it passes from the scouring case, and by so repeatedly subjecting the stock to different currents of air all foreign particles are thoroughly removed, and the stock is delivered from the machine in a thoroughly scoured and clean condition. All air pockets or closed corners, which would tend to collect material in which bacteria might thrive, are eliminated, and all of the dust is delivered to one central point.

The shoe 15 is vibrated or reciprocated from a vertical eccentric shaft 66 which is mounted in suitable bearings carried by a bracket 67 extending from the end wall of the casing. The lower end of the shaft 66 carries a friction disk 68, the lower face of which is adapted to engage against the periphery of a friction disk 69 secured by a screw 70, or other means upon the outwardly extending end of the beater shaft 44, but it is to be understood that the friction drive between the beater shaft 44 and the shaft 66 may be varied as desired. Upon the upper end of the shaft 66 is a fly-wheel

71, which absorbs vibrations due to the reciprocation of the shoe and tends to cause the shaft 66 to rotate with a uniform angular movement. The shoe 15 is connected by means of a strap or strip of suitable material 72 to the upper end of the eccentric shaft 66, and the shaft 66 may be provided with a suitable shifting lever 73 for withdrawing the disk 68 from engagement with the disk 69.

When the beater shaft 44 is driven, the eccentric shaft 66 is rotated and the shoe 15 is vibrated, and due to the movement of the main screen 23, the wheat or grain is automatically fed from the feed box to the scouring case. The friction wheel or disk 69 may be adjusted longitudinally of the shaft 44, so that it may engage the face of the friction disk 68 at different distances from its center, and this arrangement allows the eccentric shaft to be driven at different speeds, so as to regulate the number of vibrations of the shoe and thereby the amount of stock which is automatically fed from the feed-box onto the shoe. When the shoe 15 is stationary, no grain is fed from the feed-box and the transmission mechanism between the shafts 44 and 66 is noiseless in operation, and it may be easily adjusted to vary the speed of vibration of the shoe.

It is, of course, obvious that the number and size of the perforations in the screens of the shoe 15 and the angle of inclination or pitch of these screens may be varied as desired, depending upon the kind of stock being handled. It is preferable, however, to vary the speed or rate of vibration of the shoe in accordance with the kind of stock being treated, and the degree or quality of the separations desired to be obtained.

The invention is susceptible of various modifications and changes which would be within the spirit of the invention, without departing from the scope of the following claims.

Having thus described my invention, what I claim as new and desire to secure by Letters Patent is:—

1. In a machine of the class described, the combination of a grain feeding mechanism, a scouring case to which the grain passes from said feeding mechanism, a suction pipe in the path of the grain to remove impurities therefrom before passing to the scouring case, grain scouring mechanism in said case, a suction hood surrounding said scouring case and having a longitudinally-disposed air inlet extending lengthwise thereof and parallel with the scouring case, a suction pipe connected to said suction hood opposite said air inlet, a grain delivery pipe to which said scouring case delivers, and a suction pipe connected to said grain delivery pipe.

2. In a machine of the class described, the combination of grain feeding mechanism, a

scouring case to which the grain passes from said feeding mechanism, a suction pipe in the path of the grain to remove impurities therefrom before passing to the scouring case, grain scouring mechanism in said case, a suction hood surrounding said scouring case and having a longitudinally-disposed air inlet to direct a blast of air against the periphery of said scouring case and longitudinally thereof, said suction hood being provided with a depending bottom to receive impurities, a suction pipe connected to the bottom of said hood, a grain delivery pipe having a gravity delivery leg and an upwardly extending suction leg to which said scouring case delivers, and a suction pipe connected to the suction leg of said delivery pipe.

3. In a machine of the class described, the combination of grain feeding mechanism, a reticulated scouring case to which the grain passes from said feeding mechanism, a suction pipe in the path of the grain to remove impurities therefrom before passing to the scouring case, grain scouring mechanism in said case, a suction hood, the upper part of which closely surrounds said scouring case to form an annular passage between said case and hood having a longitudinal air inlet parallel with said scouring case to deliver a jet of air against the periphery of said scouring case and into said annular passage, said hood having an extended and depending bottom section below said scouring case to receive the impurities, a suction pipe connected to the bottom portion of said hood, a grain delivery pipe having a gravity leg and an upwardly extending suction leg to which said scouring mechanism delivers, means for controlling the flow of grain from said scouring case to said delivery pipe, and a suction pipe connected to the suction leg of said grain delivery pipe.

4. In a machine of the class described, the combination of grain feeding mechanism, a scouring case to which the grain passes from said feeding mechanism, a suction pipe in the path of the grain to remove impurities therefrom before passing to the scouring case, a settling chamber to which said suction pipe delivers to intercept and collect the heavier particles in the suction pipe, an outlet pipe from said suction chamber, a manual valve to control said outlet pipe, grain scouring mechanism in said scouring case, a suction hood having an air inlet to deliver a radially-disposed blast of air lengthwise of said scouring case, a suction pipe connected to said suction hood opposite said air inlet, a grain delivery pipe having a gravity leg and an upwardly extending suction leg to which said scouring case delivers, a suction pipe connected to the suction leg of said grain delivery pipe, a settling

chamber to which said last-named suction pipe delivers to intercept and collect the heavier particles, an air outlet pipe for said settling chamber, and a manual valve to control said air outlet pipe.

5. In a machine of the class described, the combination of a suction casing having suction producing means therein, grain feeding mechanism, a scouring case to which the grain passes from said feeding mechanism, a suction pipe in the path of the grain to remove impurities therefrom before passing to the scouring case leading to said suction casing, grain scouring mechanism in said case, a suction hood the upper part of which closely surrounds said scouring case having a radially-disposed air inlet delivering a blast of air longitudinally of said scouring case, a suction pipe connected to the lower part of said suction hood and leading to said suction casing, a grain delivery pipe having a gravity leg and a suction leg to which said scouring case delivers, and a suction pipe connected with the suction leg of said grain delivery pipe leading to said suction casing.

6. In a machine of the class described, the combination of a suction casing having suction producing means therein, grain feeding mechanism, a scouring case to which the grain passes from said feeding mechanism, a suction pipe in the path of the grain to remove impurities therefrom before passing to the scouring case leading to said suction casing, a settling chamber in said suction pipe between its intake and said suction casing, grain scouring mechanism in said case, a suction hood, the upper part of which closely surrounds said scouring case having a radially-disposed air inlet delivering a blast of air longitudinally of said scouring case, a suction pipe connected to the lower part of said suction hood and leading to said suction casing, a grain delivery pipe having a gravity leg and a suction leg to which said scouring case delivers, a suction pipe connected with the suction leg of said grain delivery pipe leading to said suction casing, and a settling chamber in said suction pipe between the suction leg and said suction casing.

7. In a machine of the class described, the combination with grain feeding mechanism, of a reticulated scouring case to which said mechanism delivers, grain scouring mechanism in said case, a suction hood, the upper part of which surrounds said scouring case closely adjacent thereto to form an annular space about the same, said suction hood having in its top a longitudinally-disposed air inlet slot to direct a radial blast of air against said scouring case and into the annular space, said suction hood being provided with a depending closed bottom to

receive the impurities from said scouring case, and a suction pipe connected to the bottom of said suction hood.

8. In a machine of the class described, the combination with grain feeding mechanism, of a reticulated scouring case to which said mechanism delivers, grain scouring mechanism in said case, a suction hood of substantially oblate form having an enlarged upper portion closely surrounding said scouring case and provided with a longitudinally-disposed air inlet to deliver a radial blast of air against the periphery of said scouring case, and a depending closed bottom portion to receive the impurities and a suction pipe connected to the bottom portion of said hood.
9. In a machine of the class described, the combination with grain feeding mechanism, of a reticulated scouring case to which the grain passes from said mechanism, a grain scouring mechanism in said case, a suction hood having an enlarged upper portion closely surrounding said scouring case and provided with an air inlet lengthwise thereof to discharge a radial blast of air against said scouring case, and a narrowed and closed bottom portion adapted to receive impurities, a suction pipe connected with the bottom of said suction hood, a valved delivery outlet from said scouring case, and a grain delivery pipe to which said outlet pipe delivers having a depending gravity leg and an upwardly extending suction leg.
10. In a machine of the class described, the combination of a scouring and separating casing, a suction casing independent of said scouring casing and having suction producing instrumentalities therein, grain feeding mechanism in said first-named casing, scouring mechanism to which said feeding mechanism delivers, suction means connecting said scouring casing and said suction casing and operative on the grain as it passes from the feeding mechanism to the scouring mechanism, suction means operative about and through the bottom and sides of said scouring mechanism and connecting said scouring casing and said suction casing, a grain delivery leg to which said scouring mechanism delivers the scoured and purified grain, and suction means operative on said delivery leg connecting with said suction casing.
11. In a machine of the class described, the combination of a scouring casing, a suction casing independent thereof and connected therewith by a plurality of suction conduits, grain feeding mechanism in said scouring casing, grain scouring mechanism in said scouring casing, suction producing means in said suction casing, operating means for grain feeding mechanism exterior of said scouring casing, a single shaft traversing said casings upon which said

suction producing mechanism, said scouring mechanism and said operating means for said feeding mechanism are mounted, and bearings in the outer walls of said scouring and suction casings for said shaft removably fitted to said walls and of a size to permit longitudinal withdrawal of said shaft and its scouring mechanism without disassembling them.

12. In a machine of the class described, a scouring case, a two-part suction hood about said case and comprising a casing surrounding the top and sides of the case somewhat closely and depending at its bottom beneath said scouring case, said hood having a slot extending lengthwise above said scouring case, and means for drawing a current of air through said slot and into and through said suction hood.

13. In a machine of the class described, a scouring case, a suction hood about said case and comprising a casing surrounding the top and sides of the case somewhat closely and depending at its bottom beneath said suction case, said hood having a slot extending lengthwise above said scouring case, an outlet passage leading from one end of the hood and located beneath the scouring case, and means in said outlet passage for drawing a current of air through said slot and into and through said suction hood.

14. In a machine of the class described, a scouring case, a suction hood about said case and comprising a casing surrounding the top and sides of the case somewhat closely and depending at its bottom beneath said scouring case, said hood having a slot extending lengthwise above said scouring case and a plurality of openings in one of its ends, an outlet passage leading from the other end of said hood and located beneath said scouring case, and means in said outlet passage for drawing air through said slot and openings and into and through said suction hood.

15. A machine of the kind described comprising a housing, a scouring casing horizontally arranged and supported in the housing in a central portion of the latter and toward one end thereof, a suction chamber at the other end of the housing, a suction element in said chamber, a sieving mechanism supported in the housing and disposed directly above the scouring casing to deliver stock in one end of the latter, said scouring casing being adapted to discharge stock at the other end thereof, two air conduits, one of each extending from the suction chamber to a point adjacent each end of the housing in order that a current of air will act upon the stock being fed and discharged from the scouring casing, and a suction hood surrounding the scouring casing and having connection with said suction chamber.

16. A machine of the kind described comprising a housing divided into two compart-

- ments by a substantially vertical partition, a scouring casing horizontally arranged and supported in one of said compartments in a central portion thereof, a suction element 5 in the other of said compartments, a sieving mechanism supported in the housing and disposed directly above the scouring casing to deliver stock in one end thereof, settling chambers arranged in the same compartment 10 with the scouring chamber and at one side thereof, said settling chambers having a common connection with said suction compartment, a conduit extending from each of said settling chambers to a point adjacent 15 the ends of said scouring casing, respectively, in order that a current of air will act upon the stock being fed and discharged from the scouring casing, and a suction hood surrounding the scouring casing and having 20 connection with the suction compartment.
17. In a device of the kind described comprising a housing divided into two compartments by a substantially vertical partition, a scouring casing horizontally arranged in 25 one of said compartments in a central portion of the latter, beater mechanism arranged in the scouring casing and having the shaft thereof extending through said housing, said outer compartment of the housing constitut-
- ing a suction chamber, a suction element in 30 said suction chamber and mounted on said shaft, a sieving mechanism disposed in the compartment with the scouring casing and directly over the latter to deliver stock to one end thereof, said scouring casing adapted 35 to discharge stock at the other end thereof, settling chambers arranged within the compartment with said scouring chamber and at one side thereof, a common connection between said settling chambers and said 40 suction chamber, a conduit extending from each of the settling chambers, each of said conduits being extended to points adjacent one end of the scouring casing, respectively, in order that a current of air will act upon 45 the stock being fed and discharged from the casing, a suction hood surrounding the scouring casing and having connection with the suction chamber, and each of said settling chambers having discharge openings. 50

In testimony whereof I have hereunto set my hand in presence of two subscribing witnesses.

CHARLES T. HOWSON.
